HEAD PROTECTOR

Samuel E. Bouchard, Brighton, N. Y., assignor to
 Bausch & Lomb Optical Company, Rochester,
 N. Y., a corporation of New York

Application August 18, 1943, Serial No. 499,089

7 Claims. (Cl. 2-8)

This invention relates to a head protector and more particularly to a welder's hood.

It is customary for welders to employ protectors of various types for the head to eliminate danger of injury from flying molten metal sparks or bits during the welding operation. To afford maximum protection, it has been found necessary to form the helmet of a fire-proof material to completely surround and cover the head and shoulders of the welder.

Several types of helmets heretofore proposed adequately meet these requirements; however, each possesses objectionable features. Helmets of metal construction are too heavy to be worn comfortably by the welder. Also, due to the inflexibility and unwieldiness of these helmets, the welder is cramped in his movements, especially when he is required to work in confined quarters. Cloth helmets, such as asbestos or chemically-treated fabric, have met with more favorable reception but are also objectionable in use. Their fire-proof material is impervious to air and thus prevents the ventilation and free circulation of air through the cloth and within the helmet. As it is necessary for the welder to closely inspect his work during the welding operation, the stagnant air within the helmet will absorb the heat transmitted to it by the air outside the helmet which, in turn, is heated by the extremely high temperatures generated by the torch or electric arc. As a result, due to the heat penetrating the helmet and causing the welder to perspire freely, the stagnant air within the helmet reaches its saturation point rapidly and evaporation of the perspiration stops with the consequence that the cooling effect induced by the evaporation fails with attendant physical discomfort to the welder. To relieve this discomfort, the welder is frequently required to interrupt the welding operation and remove the helmet to cool his head and permit the heated air to escape. This condition is further aggravated as the welder is often forced to lie on his back, or assume other positions, where the removal and replacement of the helmet is exceedingly difficult.

It can therefore be seen that these objectionable features militate against the practical use of these types of helmets and it is the primary object of this invention to eliminate these difficulties by the provision of a lightweight, flexible hood of fire-proof material covering the head and neck of the welder and equipped with ventilating means permitting a continuous circulation of air within the hood about the head and neck. In the preferred embodiment of the invention, the hood

is formed with air passages allowing air to enter the open bottom of the hood and pass between the head and outwardly spaced wall of the hood and through openings in the crown to the atmosphere.

5 The convective air currents passing through the hood insures the expulsion of the heated air and the entrance and passage of fresh air. Thus, the hood of the present invention obviates the inherent defects existing in prior types and provides a hood capable of being worn continuously for the entire welding operation in even confined places, with adequate protection and complete comfort. By so doing, the welder can work with maximum efficiency and accelerated production at a substantial saving in manufacturing costs.

Other objects and advantages of the present invention will appear from the following description taken in connection with the accompanying drawing in which:

20 Fig. 1 is a perspective view of the hood in use.
 Fig. 2 is a horizontal sectional view of the hood in use.

Fig. 3 is a sectional view taken on line 3-3 of Fig. 2 and also showing the hood in use.

25 Fig. 4 is an enlarged portion of a section through a fold.

In the embodiment of the invention illustrated in the drawing, referring to Figs. 1 and 2, 10 designates the body of the hood which is made of a series of stitched panels of a pliable and fire-proof material, such as asbestos or chemically-treated fabric. The body 10 completely surrounds the head and neck of the user and comprises a head portion 11 extending downwardly 30 to form a flaring shoulder portion 12.

Referring to Figs. 2 and 3, the hood is securely held in position on the head 13 of the wearer by a flexible band or drawstring 14 secured to the inner circumference of the head portion 11 at spaced intervals, as indicated at 15. In the preferred embodiment of the invention, the band 14 is secured to the head portion 11 and spaced from the peak of the hood to form an air chamber between the hood and the head of a user.

45 Heretofore, hoods designed to adequately protect the welder by shielding his head and neck from flying molten sparks or bits have been unsatisfactory in use. Metal hoods were too heavy to be worn continuously over an extended period 50 of time with comfort and due to their inflexibility, these cumbersome hoods impeded the welder in his movements, especially when working in confined places. On the other hand, cloth helmets of fire-proof material were uncomfortable in use as the hoods would not permit air to penetrate

their closely-knit material for the necessary ventilation of the interior of the hood.

The present invention obviates these objectionable features by providing a lightweight, flexible hood having means for thoroughly and continuously ventilating the helmet worn by the welder during welding. To secure this desirable result, the hood is so formed that it is substantially larger than the head of the welder and of a size that, when positioned on the head of a welder, it will be spaced therefrom to provide connected air passages in the crown and sides of the head portion 11 and in the shoulder portion 12, traversing the interior of the hood and leaving the hood through openings in the crown.

As shown in Fig. 4, the hood is permanently deformed to provide folds 16 by folding back the material of the head portion 11 to form plaits, the folded back portions being securely held in place by stitches 17. The flexible material of the hood possesses sufficient firmness to retain the folds in expanded positions when worn by the welder, yet yielding readily to external pressure. Consequently, the folds extending outwardly from the crown of the head portion 11 will assist in maintaining the crown in expanded position and thereby the air chamber formed therein.

To insure adequate ventilation of the hood, the head portion 11 is provided with air passages formed by the folds 16 spaced at intervals around the hood. These folds extend vertically from the crown of the hood to approximately the shoulder portion 12. The air enters the bottom of the hood and also through the inlet vents formed by bell-shaped portions 18 of the flaring shoulder portion 12 and flows upwardly through the air passages formed by the folds 16 to the air chamber in the crown of the hood. The air completes its passage through the hood by flowing from the air chamber in the crown through the reticulated air outlets or vents 19 disposed in openings in the crown of the hood.

To permit the continuous flow of air past the head without interference by the narrow head band 14, the folds are spaced midway between the junctures of the band 14 with the head portion 11 and extend outwardly therefrom.

It can now be seen that when the hood is in use, the hood is thoroughly ventilated by convection currents, in that the heated air flowing upwardly is evacuated from the hood through the air vents 19 to the atmosphere and the cooler air enters the bottom of the hood through the air passages formed by the bell-shaped portions 18 and through the connected air passages formed by the folds 16, circulating the air about the head of the welder and into the air chamber in the crown of the hood.

Thus, the hood of the preferred embodiment of the invention can be worn continuously with complete comfort and freedom of movement during the entire welding operation, while protecting the head and neck of the welder from injury. By so doing, the welding operation may be efficiently and expeditiously performed at substantial savings in the costs of the welded articles.

To protect the eyes of the welder from injury by the brilliant light emitted from the electric arc or torch, the front of the head portion 11 is provided with an opening in which is secured a rigid metal frame 21 adapted to engage another metal frame 22 carrying a lens 23 of eye-protecting properties. The frame 22 is secured to the head portion 11 by hinge members 24 con-

nected to a rod 25 extending through a leather strip 26 fastened to the head portion 11. To raise the lens 23 to an inoperative position above the eyes, a portion of the rod 25 extending outwardly from the leather strip 26 is bent downwardly to form a handle 27, the friction of the strip 26 on the rod 25 maintaining the lens above the eyes of the user. During the welding operation, the circulation of air through the hood will prevent any tendency of the lens 23 to become fogged by the condensation of moisture on the lens 23. To permit passage of air to the nasal passages, a hollow nose-piece 28 having a protective reticulated screen 29 is fastened to an opening in the head portion 11 below the frame 21.

From the foregoing, it will be apparent that I am able to attain the objects of my invention and provide a new and improved head protector having ventilating passages for circulating air continuously around the head of a user. Various modifications can, of course, be made without departing from the spirit of my invention or the scope of the appended claims.

I claim:

25 1. A protecting device adapted to be mounted on the head of a user comprising a hood of pliable fabric material; a plurality of folds permanently formed in the head covering portion of said hood, said folds projecting outwardly from the head 30 of the user and forming vertically extending air passages between the hood and the head of the user; and air outlets formed about the upper portions of said hood whereby air entering said hood at the bottom thereof flows upwardly through said passages to cool the head of the user and exits through said outlets.

2. A protecting device adapted to be mounted on the head of a user comprising a hood of pliable fabric material; a plurality of folds permanently 40 formed in the head covering portion of said hood, said folds projecting outwardly from the head of the user and forming vertically extending air passages between the side walls of said hood and the head of the user; an air chamber located in 45 the crown of said hood and connected to the air passages formed by said folds; air vents carried in the crown of said hood; and an attaching band secured to the side walls of said hood intermediate said folds at the base of said crown whereby air entering said hood at the bottom thereof flows upwardly through said passages into said air chamber to cool the head of the user and exits through said vents.

3. A head protecting device comprising a flexible hood made of pliable fabric adapted to cover the head and shoulders in spaced relation thereto; a plurality of folds permanently formed in said hood and forming air passages between the wall of said hood and the head of a user, 55 said folds comprising stitched plaits extending vertically at spaced intervals around said hood; and air outlets formed about the upper portions of said hood whereby air entering said hood at the bottom thereof flows upwardly through said 60 passages to cool the head of the user and exits through said outlets.

4. A head protecting device comprising a flexible hood made of pliable fabric adapted to cover the head and shoulders in spaced relation thereto; a plurality of folds permanently formed in 70 said hood and forming air passages between the wall of said hood and the head of a user, said folds comprising stitched plaits extending vertically at spaced intervals around said hood; air outlets formed about the upper portions of said

hood whereby air entering said hood at the bottom thereof flows upwardly through said passages to cool the head of the user and exits through said outlets; and a band secured to said hood intermediate said folds for fastening the hood to the head, said band permitting the free flow of air through said passages between the hood and the head of the user.

5. A head protecting device comprising a flexible hood made of pliable fabric adapted to cover the head and shoulders in spaced relation thereto; a plurality of folds permanently formed in the head covering portion of said hood, said folds projecting outwardly from the head of the user and forming vertically extending air passages between the hood and the head of the user; bell-shaped portions formed in the flaring shoulder covering portion of said hood, said portions spaced outwardly from said hood and forming air passages between the hood and the shoulders of the user connected to the passages formed by said folds; and air outlets formed in the upper portion of said hood whereby air entering said bell-shaped portions of said hood flows upwardly through said connected air passages to cool the head of the user and exits through said outlets.

6. A head protecting device comprising a flexible hood made of pliable fabric adapted to cover the head and shoulders in spaced relation thereto and having sight and respiratory openings therein; a rigid frame secured in position to the edges of said sight opening; a frame pivotally mounted above said first-named frame and adapted to be moved from an inoperative position above the eyes to an operative position before the eyes; a protective lens carried by said second-named frame; a nosepiece secured in position to the edges of said respiratory opening; a plurality of folds permanently formed in the head covering

portion of said hood for the passage of air between the hood and the head of the user; air outlets formed in the crown of said hood whereby air entering said hood at the bottom thereof flows upwardly through said passages to cool the head of the user and exits through said outlets; and means for securing said hood to the head of the user.

7. A head protecting device comprising a hood of non-inflammable pliable fabric material, said hood having sight and respiratory openings formed therein; a rigid frame secured in position to the edges of said sight opening; a frame pivotally mounted above said first-named frame and adapted to be moved from an inoperative position above the eyes to an operative position before the eyes; a protective lens carried by said second-named frame; a nosepiece secured in position to the edges of said respiratory opening; a reticulated member carried by said nosepiece; a plurality of folds permanently formed in the head covering portion of said hood, said folds projecting outwardly from the head of the user and forming vertically extending air passages between the hood and the head of the user; bell-shaped portions formed in the flaring shoulder covering portion of said hood, said portions spaced outwardly from said hood and forming air passages between the hood and the shoulders of the user connected to the passages formed by said folds; air vents formed in the upper portion of said hood and serving as exits for the air flowing through said connected passages; and a band for securing said hood to the head of the user, said band being fastened at spaced intervals to the head covering portion of said hood intermediate said folds.

SAMUEL E. BOUCHARD.
